[57] **ABSTRACT**

In the digital conversion of an analog value with the extended counting method, the discharge of a first analog memory condenser is started one beat prior to the start of the discharge of a second or main analog condenser at a relatively strong current rate (coarse encoding). When the discharge voltage of the first memory condenser reaches the reference potential, the discharge of the main condenser at the relatively strong current rate is interrupted and its discharge continues at a relatively weak current rate until the reference potential is reached (fine encoding). The discharge of the main condenser is thus performed by a plurality of currents of different, but constant intensity, having a predetermined ratio and their number is equal to the number of steps in which the condenser is discharged.

METHOD FOR THE DIGITAL CONVERSION OF AN ANALOG VALUE WITH THE EXTENDED COUNTING PROCESS

BACKGROUND OF THE INVENTION

In the digital conversion of an analog value according to the counting method, the voltage of a memory condenser is tracked by a time scanner during the period necessary to change the state of bringing it to a reference potential by means of a constant current. According to the extended counting method, the state of the memory condenser is changed in two successive steps with two currents of a predetermined ratio and each being of a different intensity. During the periods in which said change of state takes place, the counting pulses of the time scanner are counted with weighted values, the ratio of said weighted values being the same as that of the ratio of the current intensities.

As the extended counting method proceeds, the moment at which the change of state of the memory condenser with the stronger current is to be terminated and a further, partial change of state with the weaker current is to be started for an approximation of the reference potential is of particular importance. From said moment on, the pulses of the time scanner are counted with the smaller weight. The beginning of the change of state of the memory condenser with the stronger current is triggered by the time scanner, the more weighted counting pulses of which may be designated as coarse stages, whereas its less weighted counting pulses may be designated as fine stages. The change of state has to terminate in such a manner that the last coarse stage prior to reaching the reference potential is a completed one. Stated differently, after completion of the coarse encoding, the difference between the reference potential and the voltage of the condenser should not be greater than the change of condenser voltage for a single beat of the time scanner during the coarse encoding.

For the determination of the aforesaid essential moment two methods have been known heretofore.

According to one of these methods, a second reference potential is used which differs from the basic reference potential by one coarse stage. When the voltage of the memory condenser reaches the aforesaid second reference potential, then the immediately successive signal of the time scanner causes a termination of the change of state of the memory condenser with the stronger current and effects the starting of the partial recharge with the weaker current and, simultaneously, commands the start of counting the pulses of the time scanner with a correspondingly smaller weight.

The other method, although it needs only a single reference potential, requires opposing currents for changing the state of the memory condenser. During the coarse conversion, the voltage of the condenser changes its sign with respect to the reference potential and is, during its change of state with the weaker current of opposite direction, brought back to the reference potential. The less weighted pulses, too, have to be counted in a sense opposed to the count of the more weighted pulses.

The provision of two reference potentials as required by one of the known methods, or the provision of a current source and a current drain, the currents of which have a predetermined ratio, as required by the other known method, is encountered with certain difficulties.

Current sources and current drains are generally formed of controlled transistors of the type having opposed conductivity. In such a device, it is difficult to ensure a thermally synchronous operation for both types of transistors. Stated in other terms, the temperature curves of the two types of transistors are different and thus the ratio of currents of the current source and the current drain differ as a function of the temperature.

Another difficulty arises from the circumstance that in one of the known methods, the condenser has to be discharged and again partially charged during an encoding step. The iner-

tia affecting the condenser during partial changes of state is felt substantially stronger in case the sense of the change of state is altered than in case of a mere slowinG down of the discharge step.

5 Furthermore, for the change of state of the condenser by means of two current sources of opposite poles, there are required two different supply voltages for the transistors of different conductivity representing the current sources. These voltages must have a synchronous curve if the current ratio of the sources is to be maintained at a constant value.

OBJECT, SUMMARY AND ADVANTAGES OF THE INVENTION

15 It is an object of the invention to provide an improved method of the aforesaid type using an extended counting process which requires only a single reference voltage and either current sources or current drains, thus eliminating the aforesaid disadvantages.

20 The invention relates to the analog-digital conversation according to the extended counting method by changing the state of an analog memory condenser in several codirectional steps. Said change of state is performed by a plurality of currents of different, but constant intensity having a predetermined ratio and their number is identical to the number of said steps. The periods of partial change of state are measured with counting pulses of a time scanner weighted in a ratio corresponding to that of the current intensities.

According to the invention, the moment to begin the partial 30 change of state of a main analog memory condenser with the weaker current is determined with the aid of a logic circuit by means of a mark of the time scanner. Said mark follows the completion of a change of state of an additional or first analog memory condenser to the reference potential. The change of state of the first analog memory condenser is started one beat prior to the start of the partial change of state of the main analog memory condenser with the stronger current.

It is apparent from the foregoing that the method according to the invention permits the use of current sources of identical 40 polarity and thus eliminates the afore-listed difficulties which are associated with the simultaneous use of a current source and a current drain. Also, the counter runs in one sense only, since, according to the invention, the change of state of the main condenser is preformed unidirectionally. Further, the method according to the invention uses a single reference voltage.

As noted hereinbefore, the state of the additional or first 50 memory condenser is changed prior to changing the state of the condenser (also referred to as the second or main condenser) storing the signal to be encoded. When the voltage of the first memory condenser reaches the reference potential, the successive mark of the time scanner interrupts the change of state of the main condenser with the stronger current (coarse encoding) and a partial change of state with the weaker current (fine encoding) is started. The change of state of the first memory condenser starts one beat prior to starting the change of state of the main condenser with the stronger current (coarse encoding). The advance change of state of the first memory condenser renders unnecessary a second reference potential in a two-step process. The curve representing the change of state of the first condenser has to be linear only to the extent that the reference potential on the time axis is reached within a beat of the time scanner prior to the beginning of the fine encoding.

The method according to the invention may also be used for determining the breaking points of the voltage curves of one or several of a plurality of first analog memory condensers during a multi-step conversion process. The number of the additional or first analog memory condensers is dependent upon the number of steps *s* of the extended counting process according to the invention and is determined by the formula:

$$v = \sum_{v=0}^{s-1} v$$

The above formula conventionally indicates that the sum of v is taken and that v is a series of numbers starting with zero and terminating with the numeral that is $s - 1$, wherein s is the number of steps which bring the voltage of the main or second analog memory condenser to the reference potential.

The number of current sources or current drains for changing the state of all analog memory condensers is thus a function of the number of steps s and is given by the partial sum of the sth member of an arithmetic series of the third order.

A third order arithmetic series, as it is well known from the study of series and progressions in mathematics, is composed in such a manner that the sth member of such series is determined by the formula

$$A_s = A_0 + \binom{h}{1} \Delta A_0 + \binom{h}{2} \Delta^2 A_0 + \dots + \binom{h}{k} \Delta^k A_0$$

wherein $\Delta a_0 = a_1 - a_0$. Thus, an arithmetic series of the third order is used as a tool for determining the number of current sources (or current drains, as the case may be) as a function of the number of steps with which the main or second analog memory condenser is brought to the reference potential.

The invention will be better understood and further objects and advantages of the invention will become more apparent from the ensuing detailed specification of two exemplary embodiments taken in conjunction with the drawing.

In the two examples to be described, current drains are used; consequently, the change of state of the memory condensers is a discharge thereof towards a reference potential which is below the peak of the analog signal.

BRIEF DESCRIPTION OF THE DRAWING

FIG. 1 is a diagram of voltage curves of two analog memory condensers in a two-step process and of the curves of the associated switching signals;

FIG. 2 is a circuit diagram for performing a two-step process according to the invention;

FIG. 3 is a diagram of voltage curves of three analog memory condensers in a three-step process and of the curves of the associated switching signals;

FIG. 4 is a circuit diagram for performing a three-step process according to the invention;

FIG. 5 is a diagram of an electronic logic circuit for controlling the switches and the pulse counter in a three step process; and

FIG. 6 depicts the arrangement of terminals of the flip-flop circuits shown in FIG. 5 having one output designated Q and an inverse output designated $\bar{Q}$.

DESCRIPTION OF A FIRST EMBODIMENT UTILIZING A TWO-STEP PROCESS

Turning now to the diagram shown in FIG. 1, the ordinate indicates the voltage at the terminals of two analog memory condensers C_1 and C_2 , while the abscissa is the time axis which simultaneously represents a constant reference potential. The curve 1 of the switching signals represents the beats or pulses of a time scanner. The curves 2, 3, 5 and 6 are the control signals for switches S_0 - S_3 . Curves 4 and 7 indicate the output voltages of null-indicators NL_1 and NL_2 , respectively.

Turning now to FIG. 2, input terminal E of switch S_0 has applied thereto a voltage to be encoded, which may be, for example, an impulse voltage. The same voltage is applied simultaneously to a maximum detector M which may be a differentiating component. The output voltage of the maximum detector M serves to control the switch S_0 and a logic group L comprising a conventional gate structure. The output pulses of a timing generator TG are also applied to the logic group L. The logic group L emits signals s_1 , s_2 and s_3 for the actuation of the respective switches S_1 , S_2 and S_3 , shown diagrammatically as single pole switches. The latter serve to connect a current drain Se_1 to a first memory condenser C_1 and two current drains Se_2 and Se_3 to the second or main analog memory con-

denser C_2 . The current drains Se_1 - Se_3 are operably set to a constant level based on a common voltage normal supplied by a conventional transistor circuit N. The voltages appearing at the output of condenser C_1 and C_2 are applied through conductors, not shown, to two null-indicators NL_1 and NL_2 , the output voltages of which are, in turn, fed into the logic group L.

OPERATION OF THE FIRST EMBODIMENT

The operation of the circuit shown in FIG. 2 will now be described in connection with the wave forms shown in FIG. 1.

Initially, switch S_0 is closed, while switches S_1 - S_3 are open, and the condensers C_1 and C_2 are charged through the switch

15 S_0 which is part of a linear gate. At a time t_0 , the impulse voltage applied to the input terminal E has reached its peak value and the peak is sensed by the maximum detector M. Thereupon, the maximum detector M generates a signal (wave form 2 of FIG. 1) which is applied to switch S_0 causing switch S_0 to open. At that moment, there is a voltage U_x (the peak of the input voltage) to be encoded at the terminals of each condenser C_1 and C_2 .

At time t_1 , the trailing flank of a counting pulse (wave form 1 of FIG. 1) of the time scanner immediately following the moment t_0 appears, causing switch S_1 to be closed by a signal s_1 (wave form 3 of FIG. 1) from the logic group L. Closing of switch S_1 causes the condenser C_1 to be discharged through the current drain Se_1 . The discharge voltage curve of the condenser C_1 is linear and has a rising negative slope corresponding to the coarse encoding (four fine stages per beat). Discharge of C_1 continues until the reference potential is reached represented by the zero line or abscissa. This point and the output of the time scanner control the moment t_3 at which switching is performed from the coarse encoding to the fine encoding.

25 The switching moment or time t_3 is determined by the trailing flank of a counting pulse of the time scanner that immediately follows the point in time when the reference potential is reached. Referring to FIG. 1, it will be seen from the curve for C_2 that the discharge of C_2 for both coarse and fine encoding is at a constant but different rate or intensity.

30 Switches S_2 and S_3 are closed at time t_2 , one beat after the start of the discharge of condenser C_1 as illustrated by wave forms 5 and 6 of FIG. 1 corresponding to output signals s_2 and s_3 , whereupon the two current drains Se_2 and Se_3 discharge the condenser C_2 with a current $i + (p - 1) \cdot i = p \cdot i$. This equation means that the discharge current of the main or second analog memory condenser is formed of two currents, that is, current i and current $(p - 1) \cdot i$. The first-named current is taken up by the current drain Se_2 , whereas the second current is taken up by the current drain Se_3 . As indicated in line 11 of page 11, the sum of these two partial currents equals $p \cdot i$, wherein p is a proportionality factor with which the counting pulses are weighted during discharge with higher current. The aforesaid discharge of the condenser C_2 continues until the condenser C_1 has reached the reference potential and the immediately successive trailing flank of a counting pulse has appeared. The value p is the weight with which the counting pulses are counted in a counter, now shown, during the coarse encoding in the period from t_2 to t_3 .

35 At time t_3 , the switch S_3 is again opened due to the discontinuance of output signal s_3 (wave form 6 of FIG. 1) under the control of logic group L. Thereupon condenser C_2 discharges only with a current i , designating the start of fine encoding which terminates when the voltage at the condenser C_2 reaches the reference potential corresponding to time t_4 . During the period from t_3 to t_4 , the counting pulses of the time scanner are counted with a weight of 1.

40 The course of the discharge voltage of the condenser C_1 has to be accurate only to the extent that it reaches the reference potential during the beat of the time scanner preceding the moment t_3 . The switching from coarse encoding to fine encoding is triggered at time t_3 by a signal emitted from a two input

AND-circuit (not shown) contained in the logic group L. One input to the AND-circuit corresponds to reaching the reference potential by C_1 , while the other input corresponds to the appearance of the trailing flank of a beat of the time scanner following the moment when the reference potential is reached.

The advantage of the afore-described method according to the invention resides in the fact that only current generators, for example, current drains, are required, the synchronous operation of which is easily achieved. Further, they may be controlled by the same reference voltage. Also, only a forward counting is required. Thus, there is no need for a counter adapted to be actuated by counting pulses proceeding in different counting senses.

DESCRIPTION OF A SECOND EMBODIMENT UTILIZING A THREE-STEP PROCESS

In FIG. 3 there is shown the course of the discharging voltages of analog memory condenser C_{13} , C_{23} , C_{33} and C_{43} , together with the graphs of the associated control or switching signals which serve to control switches S_{63} - S_{73} in a three-step encoding process.

In FIG. 4 there are shown the four analog memory condensers C_{13} - C_{43} of the three step process together with eight switches S_{63} - S_{73} and seven current drains. The condensers C_{13} , C_{23} and C_{33} by means of their discharge voltages, together with the output of beat generator TG_3 establish moments for controlling the discharge of the condenser C_{43} in a manner similar to that described in connection with the two-step process.

Referring to FIG. 5, there is shown an electronic logic circuit, one input terminal E_3 of which receives a signal pulse to be encoded. Four further input terminals are associated with null-indicators NL_{13} , NL_{23} , NL_{33} and NL_{43} , respectively, for receiving the voltage of the four corresponding memory condensers C_{13} , C_{23} , C_{33} and C_{43} , shown in FIG. 4.

The signal pulse proceeds from the input E_3 simultaneously to a linear gate LT_3 (which includes switch S_{63}), a base point indicator FI and to one input of a maximum base point indicator FMI . The linear gate LT_3 has an output which is connected with the charge input terminals of the four condensers C_{13} , C_{23} , C_{33} or C_{43} as illustrated in FIG. 4. A second input of the maximum base point indicator FMI is connected with the output of the base point indicator FI . The output signal of the maximum base point indicator FMI is applied to the beat input of a flip-flop circuit FF_8 functioning as a reducer.

The arrangement of terminals on the rectangle representing the flip-flop circuit FF_8 (as well as flip-flop circuits FF_2 , FF_3 , FF_6 and FF_7 to be discussed later) shown in FIG. 5, is depicted in FIG. 6. The Q output of the reducer FF_8 is connected with the reset inputs of a plurality of other flip-flop circuits, all of the master-slave type in this embodiment. The $\bar{Q}$ output of the reducer FF_8 is applied to a second input of the linear gate LT_3 . As previously noted, switch S_{63} of FIG. 4 is part of the linear gate circuit LT_3 and is opened by command of the Q output signal of the flip-flop circuit FF_8 .

Beat generator TG_3 has its output connected to a reducing flip-flop circuit FF_1 , the Q output of which is connected to the beat input of a second flip-flop circuit FF_2 . The Q output of FF_2 generates signals s_{23} , s_{33} for the control of switches S_{23} and S_{33} , respectively, shown in FIG. 4. The $\bar{Q}$ output of flip-flop circuit FF_2 is connected to one input of a two-input gate G_5 , having an output signal s_{43} which controls switch S_{43} of FIG. 4.

One input of an NAND gate G_4 is connected with the Q output of the flip-flop circuit FF_2 , while the other input of the gate G_4 is directly connected with the Q output of the reducing circuit FF_1 . The output of the gate G_4 is applied to the beat input of flip-flop circuit FF_3 , the Q output signal s_{53} of which controls the switch S_{53} of FIG. 4. The $\bar{Q}$ output of the flip-flop circuit FF_3 is connected to one input of two, two input gates G_6 and G_7 , the respective output signals s_{63} and s_{73} of which control the switches S_{63} and S_{73} of FIG. 4.

The output signals of the beat generator TG_3 are further applied to the beat input of flip-flop circuit FF_4 , the Q output signal s_{13} of which controls the switch S_{13} of FIG. 4. The inverter outputs of the null-indicators NL_{13} , NL_{23} and NL_{33} are connected, respectively, with one input of two input NAND gates G_1 , G_3 , and G_2 . The other inputs of the last-named three gates are connected to the output of a negation circuit G_0 which has its input connected to receive the output signal of the beat generator TG_3 .

10 The respective outputs of the NAND gates G_1 , G_3 and G_2 are connected with the beat inputs of three flip-flop circuits FF_5 , FF_6 and FF_7 . The Q output of the flip-flop circuit FF_5 is connected to a second input of the gate G_6 which has its other input connected to the Q output of flip-flop circuit FF_2 . The Q output of the flip-flop circuit FF_6 is connected to a second input of the gate G_6 and the Q output of the flip-flop circuit FF_7 is connected to a second input of the gate G_7 . The $\bar{Q}$ output of the flip-flop circuit FF_6 is applied to an input of an 15 NAND gate G_8 . The corresponding input of a second NAND gate G_9 is connected with the Q output of the flip-flop circuit FF_7 . The two other inputs of the NAND gates G_8 and G_9 are connected with the Q output of the flip-flop circuit FF_3 .

19 The respective outputs of gates G_8 and G_9 are connected 25 with the control inputs P_0 and P_1 of a counter Z_3 to control the weight of the counting pulses. A third control input P_2 of the counter Z_3 is directly connected with the Q output of the flip-flop circuit FF_3 , while the beat input of the counter Z_3 is connected with the output of a three input NAND gate G_{10} . To 30 one input, serving as a starting input, there is connected the Q output of the flip-flop circuit FF_5 ; to a second input there is applied, through the negation circuit G_0 , a signal corresponding to the beat or timing pulses of beat generator TG_3 , while the third input of gate G_{10} is connected with the output of null-indicator NL_{43} which generates a signal when the voltage of the condenser C_{43} of FIG. 4 has reached the reference potential. The third input of the gate G_{10} thus serves as a stop input so as to cause the circuit to discontinue counting. The output 35 of the null-indicator NL_{43} , with which the voltage of the main condenser C_{43} proper is controlled, is applied to the input of a monostable flip-flop circuit MF_1 . The output of MF_1 is coupled to the input of a second monostable flip-flop circuit MF_2 . The output of MF_2 is, in turn, connected to the reset input of 40 45 reducing circuit FF_8 , the output of which controls the switch S_{63} .

OPERATION OF THE SECOND EMBODIMENT

The operation of the afore-described logic circuit will now be set forth with reference to FIGS. 3 and 4.

At time t_{03} a signal pulse E_3 is generated, and the base point indicator FI is caused to emit an output signal (curve 2 in FIG. 3). Practically simultaneously therewith, the maximum base point indicator FMI also emits an output signal (curve 3 in FIG. 3), while all memory condensers C_{13} , C_{23} , C_{33} , C_{43} begin to charge up through switch S_{63} which is closed. At time t_{13} the signal pulse reaches its maximum and all capacitors are charged. Thereupon, as seen, the output signal of the maximum base point indicator FMI is cut off. This switches the reducer flip-flop circuit FF_8 . Its Q output signal s_{63} (curve 4 in FIG. 3) is applied to flip-flop circuits FF_1 - FF_8 to cause the flip-flop circuits to assume a stand-by condition. The Q output signal of the flip-flop circuit FF_8 is applied to gate LT_3 so as to open switch S_{63} . Upon cut-off of the Q output signal of flip-flop circuit FF_8 at the end of the encoding cycle, all flip-flop circuits contained in the logic circuit are reset.

The first trailing flank of the beat signal (curve 1 in FIG. 3), following the moment t_{13} and occurring at the moment t_{23} , 70 closes the switch S_{13} by means of the Q output signal s_{13} (curve 5 in FIG. 3) of the flip-flop circuit FF_4 . The reducing circuit FF_1 is also actuated by the trailing flank of the beat pulse appearing at moment t_{23} . The trailing flank of the Q output signal of the flip-flop circuit FF_1 actuates the flip-flop circuit FF_2 and the latter with its Q output signals s_{23} and s_{33} , closes the respec-

tive switches S_{23} and S_{33} at moment t_{33} . Thus, the condensers C_{23} and C_{33} of FIG. 4 are discharged.

The Q output signals of the flip-flop circuits FF_1 and FF_2 are represented by curves 6 and 7, respectively, in FIG. 3. At moment t_{33} , the signal taken from the Q output of the flip-flop circuit FF_2 closes the switch S_{43} through the gate G_5 by means of an output signal s_{43} (curve 8 in FIG. 3). The switch S_{43} is reopened at the moment t_{63} by means of the first trailing flank of the beat signal following the moment t_{53} . This moment is determined by the null-indicator NL_{13} which emits a signal when the voltage of the condenser C_{13} has reached the reference potential. Said last-named signal is applied through the gate G_1 to a flip-flop circuit FF_3 which, in response, emits an output signal (curve 9 in FIG. 3) applied to the gate G_5 . Meanwhile, through flip-flop circuit FF_2 , a leading flank of the output signal of the reducer FF_1 actuated the gate G_4 which, in turn, energizes the flip-flop circuit FF_3 , at the Q output of which there appears a signal s_{53} (curve 10 in FIG. 3) which closes the switch S_{53} of FIG. 4. Simultaneously, the $\bar{Q}$ output signal of the flip-flop circuit FF_3 is applied to gates G_6 and G_7 which emit output signal s_{63} (curve 13) and s_{73} (curve 11), respectively, closing the associated switches S_{63} and S_{73} . At this point the flip-flop circuit FF_7 is energized by the null-indicator NL_{23} through the gate G_2 , and generates at its Q output and output signal (curve 12 in FIG. 3) which affects the gate G_7 in such a manner that upon the appearance of the successive trailing flank of the beat signal at moment t_{43} , it cuts off the output signal S_{73} of the gate G_7 and, as a result, the switch S_{73} is opened.

The flip-flop circuit FF_6 is actuated in response to the presence of an output signal at the output of null-indicator NL_{33} when the voltage of condenser C_{33} reaches the reference potential at moment t_{33} to generate a signal (curve 14 in FIG. 3) at its Q output which is applied to gate G_6 . This causes output signal s_{63} of gate G_6 to be cut off as soon as the successive trailing flank of the beat signal appears.

The output signals at the $\bar{Q}$ output terminals of the flip-flop circuits FF_6 and FF_7 control simultaneously the respective weight inputs P_0 and P_1 of the counter Z_3 through gates G_8 and G_9 . The output signal (curve 15 in FIG. 3) of null-indicator NL_{43} controls the monostable flip-flop circuits MF_1 and MF_2 which cause a reset signal to be applied to the reducing circuit FF_8 . The output signals of the monostable flip-flop circuits MF_1 and MF_2 are represented by curves 16 and 17, respectively. As soon as the reset signal is received at FF_8 , its Q output causes flip-flop circuits FF_1 - FF_7 of the logic circuit to be reset, indicating the completion of an encoding cycle.

SUMMARY OF THE SPECIFICATION

The specification discusses two embodiments; the first one, illustrated in FIGS. 1 and 2, practices the invention in its simplest form, i.e., it discloses a two-step process, while the second embodiment illustrated in FIGS. 3 and 4 deals with a three-step process.

The first embodiment contains a sole additional or first analog memory condenser C_1 and a sole main or second analog memory condenser C_2 .

The second embodiment is evidently more complex, since here a three-step process is practiced, necessitating a substantial increase in the number of condensers.

In the first embodiment a clear line can be drawn that separates the mode of operation of the first condenser C_1 and the second condenser C_2 . Clearly, the additional or first condenser C_1 is discharged by the relatively strong current to the reference potential while the main or second condenser C_2 undergoes a two-step discharge, one with the relatively strong current up to moment t_3 and thereafter a second with a weak current.

The aforesaid clear difference in operation is less apparent in the more complex second embodiment where a total of four condensers are present. Here the number of the additional or first analog memory condensers is more than one,

while the number of the main or second analog memory condenser is still one and is identified as C_{43} . It is noted that in the second embodiment a number of first or additional analog memory condensers behave during operation similarly to the main or second analog memory condenser C_2 of the first embodiment.

It is noted that the term "change of state" is intended to cover either a charging or a discharging of the condensers. In both exemplary embodiments discharging takes place, this is 10 why current drains and not current sources are described.

Examples will now be given to calculate, with the aid of formula

$$\sum_{v=0}^{v=s-1} v$$

the number of first analog memory condensers when the number of steps in the process is known.

Thus, the first embodiment concerns a two-step process, consequently $s=2$ and therefore $v=0, 1$.

The second embodiment is a three-step process, thus $s=3$ and consequently, $v=0, 1, 2$.

Thus, since in the first embodiment $v=0, 1$ it follows that $\Sigma 25 v = 0 + 1 = 1$. This result is confirmed since in the first embodiment there is one first analog memory condenser C_1 .

Since in the second embodiment $v=0, 1, 2$, $\Sigma v = 0 + 1 + 2 = 3$. Again, this result is confirmed since the embodiment as shown in FIG. 4 has three first analog memory condensers C_{13} , 30 C_{23} and C_{33} .

That which is claimed is:

1. In a method for the digital conversion of an analog value by the extended counting process, said method being of the known type wherein the change of state of an analog memory condenser for bringing the voltage thereof to a reference potential is effected in a plurality of successive codirectional steps with a plurality of currents equaling the number of said steps, said currents having a constant, differing intensity of predetermined ratio, the timing of the changes of state of said analog memory condenser being effected with beats of a time scanner, said beats being weighted in a ratio identical to that of said current intensities, the improvement comprising the following steps:
  - A. bringing the voltage of a plurality of analog memory condensers to the analog value to be encoded,
  - B. changing the state of a first analog memory condenser with a relatively strong current bringing the voltage of said first analog memory condenser to a predetermined value,
  - C. changing the state of a second analog memory condenser towards said reference potential with said relatively strong current,
  - D. terminating step (C) in a timed relation to the attainment of said predetermined voltage value by said first analog memory condenser, and
  - E. changing the state of said second analog memory condenser towards said reference potential with a relatively weak current, starting step (E) simultaneously with step (D).
2. A method as defined in claim 1, wherein said predetermined voltage value is identical to said reference potential.
3. A method as defined in claim 1, wherein step (C) is started subsequent to the start of step (B).
4. A method as defined in claim 1, wherein step (C) is started by the beat of said time scanner immediately following the start of step (B).
5. A method as defined in claim 2, wherein step (D) and the start of step (E) are effected by the beat of said time scanner immediately following the attainment of reference potential by the voltage of said first analog memory condenser.
6. A method as defined in claim 1, wherein at least steps (C) - (E) are triggered by a logic circuit.
7. A method as defined in claim 1, wherein at least two first analog memory condensers are used, the moment of terminat-

ing the change of state of at least one first analog memory condenser with a relatively strong current and continuing a change of state of the last named condenser with a relatively weak current is determined by means of said method.

8. A method as defined in claim 7, wherein the number of said first analog memory condensers is determined by the formula

$$\sum_{v=0}^{v=s-1} v$$

wherein s is the number of steps for bringing the voltage of said second analog memory condenser to said reference potential.

9. A method as defined in claim 8, wherein the number of means necessary to cause current flow for changing the state of said condensers is the sth member of an arithmetic series of the third order.

10. A method as defined in claim 9, wherein said means necessary to cause current flow are current drains.

UNITED STATES PATENT OFFICE
CERTIFICATE OF CORRECTION

Patent No. 3,678,502 Dated July 18, 1972

Inventor(s) Eberhard Kienzler

It is certified that error appears in the above-identified patent and that said Letters Patent are hereby corrected as shown below:

In the heading, under [30] Foreign Application Priority Data, the date should read --March 24, 1969--.

Col. 2, line 3, "slowinG" should reading --slowing--; line 20, "conversation" should read --conversion--; line 44, "preformed" should read --performed--.

Col. 3, line 28, "i" should read --in--; line 43, "perForming" should read --performing--; line 75, "SE₃" should read --Se₃--.

Col. 4, line 61, "now" should read --not--.

Col. 5, line 27, "meanS" should read --means--; line 50 "FE₈" should read --FF₈--.

Col. 6, line 63, "Q" should read --Q--.

Col. 7, line 17, "as" should read --has--.

Signed and sealed this 2nd day of January 1973.
